UNITED STATES PATENT OFFICE.

ALPHEUS O. WILBUR, OF DAVIS, MICHIGAN.

VEHICLE-SPRING.

SPECIFICATION forming part of Letters Patent No. 268,582, dated December 5, 1882.

Application filed August 2, 1882. (No model.)

To all whom it may concern:

Be it known that I, ALPHEUS O. WILBUR, of Davis, in the county of Macomb and State of Michigan, have invented new and useful 5 Improvements in Vehicle-Springs; and I do hereby declare that the following is a full, clear, and exact description thereof, reference being had to the accompanying drawings, which form a part of this specification.

10 The nature of this invention relates to certain new and useful improvements in the construction of springs for wheel-vehicles of that class which are provided with bolsters upon which the body or box rests; and the invention 15 consists in the peculiar construction and combination of parts, as more fully hereinafter described.

Figure 1 is a perspective view of my improved spring. Figure 2 is an elevation from 20 the opposite side.

In the accompanying drawings, which form a part of this specification, A represents two coil-springs of equal size inclosed between the top plate, B, and the bottom plate, C, the whole 25 being secured together by means of the bolts D, the parts being so arranged with relation to the bolts that when the springs are compressed by pressure upon the top plate the lower ends of the bolts will project through the 30 bottom plate. The bottom plate is provided with the ears a, designed to embrace the wagon-stake, and the top plate is provided with the lugs d, coincident in vertical position to the lugs a, and it performs the double office of em-

bracing the upper portion of the wagon-stake, 35 and furnishing a flange against which the side of the wagon-body rests. The bottom plate is also provided with downwardly-projecting flanges c, which embrace the sides of the bolster, upon which the whole device rests. The 40 ears a are designed to be secured to the stake by a bolt passing through said ears and the stake through the hole b. In practice four of these springs are required—one at each end of the front and rear bolsters—and by their use a 45 very cheap and effective spring is obtained.

I am aware of Patent No. 256,564, of 1882, in which duplex springs are housed in a casting which rests upon the bolster, and such construction is not sought to be covered in this 50 application.

What I claim as my invention is—

1. The bottom plate, which forms the bed for the springs, having flanges to embrace the bolster and perforated ears to embrace the 55 wagon-stake, and be secured thereto, combined with the top plate having flanges to embrace the said stake near its upper extremity, the springs, and bolts, as set forth.

2. In combination with a bolster, its stake, 60 and the body of a wagon, the bed-plate C, having lugs c and ears a, perforated at b, the top plate, B, having ears d, the bolts D, and the springs A, as and for the purposes set forth.

ALPHEUS O. WILBUR.
